UNITED STATES PATENT OFFICE.

HERMANN FAEHRMANN, OF NEW YORK, N. Y.

PROPELLER.

1,073,413.

Specification of Letters Patent. Patented Sept. 16, 1913.

Application filed September 30, 1910. Serial No. 584,620.

To all whom it may concern:

Be it known that I, HERMANN FAEHRMANN, a citizen of the United States, and resident of the borough of Brooklyn, county of 5 Kings, city and State of New York, have invented certain new and useful Improvements in Propellers, of which the following is a specification.

My invention relates to propellers of the 10 screw type, and is adapted for use especially in the propulsion of air-ships and boats, but may be employed for other purposes also.

The object of my invention is to produce 15 a propeller which will be light yet very strong and rigid, so that it may be rotated at a very high rate of speed. Through experience I have acquired the conviction that progress and success in aerial navigation will depend largely on the use of high-speed 20 propellers.

To accomplish the above-indicated result, I construct the propeller blades and secure them in a novel manner fully described hereinafter with reference to the accompanying 25 drawings, in which—

Figure 1 is an end view of a propeller constructed according to my invention and comprising two sets of blades; Fig. 2 is a similar view of a propeller comprising four 30 sets of blades; Fig. 3 is a longitudinal vertical section, taken through the center of either Fig. 1 or Fig. 2; Figs. 4 and 5 show one of the blades in edge view and face view respectively; Fig. 6 is a cross section on 35 line 6—6 of Fig. 5; Fig. 7 shows a propeller of the character represented in Fig. 2, in combination with a surrounding rim; Fig. 8 shows a hub with two blades projected at opposite sides thereof; Fig. 9 is a face view, 40 with parts in section, of a construction in which a coil is used to hold the blades, and Fig. 10 is a similar view of still another construction.

In carrying out my invention, the individual blades are narrow, and several of them (six in Figs. 1, 2, 3, 7, 9 and 10) form a set which takes the place of one of the wide blades of usual propellers. These narrow blades A taper from the center to 45 their outer ends, in order that they may be able to better withstand the strains produced by centrifugal force and by pressure.

As shown, the pitch angle of the blades is very small, not exceeding 15°, and the use of such a small pitch angle I consider a novel 55 and useful feature of my invention. The proportion of blade width to blade length is about as 1:3, in the example illustrated. When rotated at high velocities, the strains on the blades are largely tensile strains. 60

The cross section of the individual blades will vary according to the requirements of each case. I prefer to make the blades with a flat driving surface A' and with a round surface A² on the back, but they could be 65 made concave on the driving side.

Various means may be employed for assembling the blades. According to Figs. 1 to 6, the blades A are provided with segmental feet A³ adapted to engage the propeller shaft B. The outer portions of the blades are bent as shown in Fig. 3 so that the driving surfaces A' will stand at the proper angle or pitch to a plane perpendicular to the shaft. The feet A³ also form 70 means for spacing the blades of the same set (see Fig. 3) and for the sake of greater strength, and particularly to prevent the blades from flying out radially under the influence of centrifugal force, I employ 75 rings or hubs C engaging the outer surfaces of the feet A³ and the straight inner portions of the blades A, there being as many hubs as there are blades in each set, that is to say, six in the particular case illustrated. 80 The rings or hubs C also assist in spacing the blades lengthwise of the shaft. They are placed immediately adjacent to the bent or twisted portions of the blades. A collar or washer D may be provided to engage the 85 blades at one end of each set, the blades and the hub C at the other end being engaged by a nut E screwing on the shaft. Another nut E' screws on the shaft and presses against the washer D. Of course, other means 90 might be employed for clamping or otherwise securing the blades in position.

The structure shown in Fig. 3 will hold two sets of blades in position, as shown in Fig. 1, or four sets, as in Fig. 2, or in fact 100 any number of sets that the peripheral width of the feet A³ will allow to be placed on the shaft B. As long as the nut E is loose, all the blades may be adjusted individually,

circumferentially of the shaft, and when they have been given the desired position, they are clamped or locked by tightening the nut E. The outer ends of the blades may 5 be secured to and held by a flat rim F. (Fig. 7) of sufficient width to engage all the blades.

Instead of employing hubs C separate from the blades, I may connect blades and hubs rigidly. Thus in Fig. 8 the hub C' 10 has two blades A⁴ projected therefrom in diametrically opposite directions, and it will be obvious without further explanation how this construction may be used for a propeller of the type shown in Fig. 1.

15 Instead of employing a set of hubs, I may provide a continuous elastic hub or holder C² of spiral or coiled shape, as shown in Fig. 9, the convolutions of this coiled hub having a pitch corresponding to that of the 20 blades A and engaging the flat front and curved back of each blade so as to hold it in position. The feet A³ would in this case be oblique to the shaft B, and properly concaved to fit the shaft. Nuts E², check nuts 25 E³ and a washer D' are shown as means for compressing the coiled hub C² and thus clamping the blades A in position. Finally, as represented in Fig. 10, the blades (of the same construction as in Fig. 9) are clamped 30 between individual rings or annular hubs C³ each of which is provided with an angular recess C⁴ disposed obliquely, and adjoining hubs are so placed that their recesses will register to receive and hold the blades. 35 While the drawing seems to show such adjoining hubs in contact with each other, there is in reality a very small space between them, so that the endwise pressure exerted by the nuts E² will clamp the blades 40 A between the adjacent rings or hubs C³.

It will be understood that various modifications may be made without departing from the nature of my invention.

While the device has been described as a 45 propeller, it will be evident that it may also be employed as a fan or ventilator and for other purposes, as for pumping, in which case it may be run in the opposite direction.

The improved construction herein described 50 will enable the propeller to be rotated at a very high rate of speed without danger of bursting or other injury, or of deformation, since the material is subjected chiefly to tensile strains. A very high efficiency is 55 thus obtained.

The propeller may be driven direct (that is to say, without interposing a speed-reduction gear) from any high speed motor, such as, for example, a steam turbine or gasoline engine.

I claim as my invention:

1. A structure adapted for use as a propeller or for other purposes, comprising a shaft, blades mounted thereon at an angle to 65 the axis of rotation, and a hub structure

having spacing portions which extend around the entire circumference of the shaft and separate the blades axially.

2. A structure adapted for use as a propeller or for other purposes, comprising a 70 shaft, blades mounted thereon in spiral relation to each other and provided with segmental feet fitted to the shaft said feet extending lengthwise of the shaft and engaging adjacent blades and means for securing 75 said blades.

3. A structure adapted for use as a propeller or for other purposes, comprising a shaft, blades mounted thereon in spiral relation to each other, ring-shaped hubs arranged between the blades, and means for holding the blades and hubs together. 80

4. A structure adapted for use as a propeller or for other purposes, comprising a shaft, blades mounted thereon in spiral relation to each other, ring-shaped hubs arranged between the blades and provided at 85 their edges with recesses to receive the blades and means for holding the blades and hubs together.

5. A structure adapted for use as a propeller or for other purposes, comprising a shaft, blades mounted thereon in spiral relation to each other and provided with inner portions normal to the shaft and with outer 90 portions oblique thereto, ring-shaped hubs arranged between the inner portions of said blades, and means for holding the blades and hubs together.

6. A structure adapted for use as a propeller or for other purposes, comprising a shaft, blades mounted thereon at different points of the shaft's length, a ring-shaped hub arranged between the blades, and means for holding the blades and hub together. 100

7. A structure adapted for use as a propeller or for other purposes, comprising a shaft, annular end hubs on the shaft blades mounted on the shaft at different points of its length between said hubs; a ring-shaped hub arranged between the blades all of said hubs being provided at their edges with recesses to receive the blades, and means for holding the blades and hubs together. 110

8. A structure adapted for use as a propeller or for other purposes, comprising a shaft, blades mounted thereon at different points of the shaft's length and provided with inner portions normal to the shaft and with outer portions oblique thereto, a ring-shaped hub arranged between the inner portions of said blades, and means for holding the blades and hub together. 115

9. A structure adapted for use as a propeller or for other purposes, comprising a shaft, blades mounted thereon, ring-shaped hubs provided at their edges with recesses to receive the blades, and means for holding together the blades and the hubs. 125

10. A structure adapted for use as a prop- 130

peller or for other purposes, comprising a shaft, blades mounted thereon and provided with feet projecting lengthwise of the shaft, and ring-shaped hubs arranged between the 5 blades and surrounding said feet.

In testimony whereof, I have signed this

specification in the presence of two subscribing witnesses.

HERMANN FAEHRMANN.
